UNITED STATES PATENT OFFICE

ALFRED L. GRISÉ, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS

LIQUID DISPENSING APPARATUS

Application filed June 18, 1929. Serial No. 371,854.

- This invention relates to improvements in liquid dispensing apparatus, such for example, as is suitable for dispensing gasoline and the like in measured quantities.
- More particularly, the invention relates to that type of apparatus having two measuring cylinders, arranged so that one fills while the other discharges and provided with controlling valve mechanism, which automatically operates at the proper time,—no attention being required of the operator except to pump, or control the pumping means, by which liquid is supplied under pressure alternately to the measuring cylinders.
- The invention, in one of its aspects, also relates to that special type of apparatus, wherein each measuring cylinder is provided with a piston and the pistons are interconnected by means in part of a resilient nature, the arrangement being such that one piston, moving under liquid pressure on its filling stroke, moves the other on its discharge stroke and also such that the resilient part of the connection is stressed during the latter part of the filling stroke of each piston and later imparts a spring impulse to that piston to start it on its discharge stroke. Such arrangement contemplates that either piston, which is forcing out liquid from its measuring cylinder, will complete its work well ahead of the time when the other piston has completed its stroke in the measuring cylinder which is being filled. The apparatus, under normal conditions, will work in this way without trouble. However, under certain conditions, such as abnormally fast pumping or restrictions in the discharge passage or hose, one piston can be made to complete its filling stroke before the other completes its discharge stroke because the resilient part of the aforesaid connections may yield before the appointed time.
- This invention has for one object the provision of means for preventing the difficulty just described. This object is accomplished by providing two locks for the valve mechanism, one of which will be released by either piston at the end of its filling stroke and the other of which will be released by either piston at the end of its discharge
- stroke. Before the valve mechanism can operate to change the direction of flow to and from the two measuring cylinders, both locks must be released and, when this is accomplished, both of the desired conditions, prerequisite for proper timing of the valve mechanism, prevail and improper operation in the manner above stated, is prevented.
- Another object of the invention is to provide improved valve mechanism and, in particular, an arrangement of valves, one in the base of each cylinder, to eliminate any passage of pocket between the base of the cylinders and the valve or valves, in which liquid can collect without being delivered immediately through the hose.
- Other features of the invention will appear from the following description and will be pointed out in the appended claims.
- The invention will be disclosed with reference to the accompanying drawings, in which:—
- Figs. 1 and 2 are front and side elevational views of the dispensing apparatus;
- Fig. 3 is a fragmentary sectional elevational view of one of the measuring cylinders showing its piston and the float-operated air valve therein;
- Fig. 4 is a sectional plan view taken on the line 4—4 of Fig. 3;
- Fig. 5 is a view taken similarly to Fig. 3 but showing the float valve in a different position;
- Fig. 6 is a fragmentary elevational view of one of the measuring cylinders, taken from the same direction as Fig. 2 but showing the hood in section;
- Fig. 7 is a sectional elevational view, the upper portion of which is taken along the line 7—7 of Fig. 2 and the lower portion of which appears as it would if the enclosing casing were removed;
- Fig. 8 is a sectional view of the lower portion only of the apparatus, such view being taken at right angles to Fig. 7 and substantially along the line 8—8 of Fig. 1;
- Figs. 9 and 10 are front and rear elevational views, respectively, of the intermediate section of the apparatus, showing the valve

operating and locking mechanism and associated parts;

Fig. 11 is a sectional view taken at right angles to Figs. 9 and 10 and illustrative of the same mechanism;

Fig. 12 is a sectional plan view taken on the line 12—12 of Fig. 9;

Fig. 13 is a sectional plan view taken on the line 13—13 of Fig. 14;

10 Fig. 14 is a sectional elevational view taken on the line 14—14 of Fig. 12; and

Fig. 15 is a fragmentary view, taken similarly to Fig. 12 but with the valves removed to clearly reveal the underlying ports.

15 The dispensing apparatus includes two measuring cylinders 20 (Fig. 7), usually of glass or other suitable transparent material and each containing a suitable piston 21. Each piston (see Fig. 3) has one or more air

20 passages 22 therethrough, which are opened and closed under the control of a float 23. Each piston has fixed thereto a piston rod 24, extending downwardly through the common base casting 25, on which the measuring cylinders are supported. These rods are connected together in any suitable way, preferably by a flexible member, such as the sprocket chain 26, so that the pistons are forced to move in opposite directions. Interposed in

25 30 the connections between rods 24 are elastic means, such as one or more springs 27.

Liquid under pressure is supplied to the measuring cylinders alternately, at points beneath their pistons, under the control of 35 suitable valve means, herein shown as individual ported disc valves 28, which are interconnected to be operated simultaneously and extremely rapidly by a single spring impulse driving mechanism, such as that shown in 40 Fig. 9,—the drive spring of which is marked 29. The arrangement is such that, when either valve 28 is positioned to admit liquid to the base of one measuring cylinder, the other valve is so positioned as to permit its 45 contents to discharge through the outlet 30 and into hose 31. Thus, the piston, rising in one cylinder under the pressure of the pumped liquid, communicates a force through the chain 26 and springs 27 to the other piston, whereby the latter forcibly discharges 50 the liquid previously admitted therein.

The stroke of each piston is adjusted so as to displace a definite measured quantity of liquid from its cylinder. Each piston is positively limited in its stroke,—at one end by the abutment of the lower face of the piston with the upper face of casting 25, which forms a lower head for both cylinders, and on the up stroke by the engagement of an 55 60 abutment 32 on the piston with an overlying fixed, but adjustable, abutment 33. The strokes of the two pistons may not be exactly equal because of inequalities in the glass cylinders 20, which are seldom exactly equal or 65 uniform in bore. The elastic means 27 in the

connections between the pistons compensates for such differences in strokes and enables one piston to move, if necessary, to reach the limit of its stroke in one direction, after the other has reached the limit of its stroke in the other 70 direction.

By preference, I utilize the elastic means 27 for imparting a spring impulse to each piston to initiate its downward and discharge stroke. In such a case, the connections between the pistons are so arranged that each piston will normally reach the end of its discharge or downward stroke before the other has completed its filling or upward stroke, as will be clear from Fig. 7. In this 80 way, continued movement of the rising piston after the other piston has stopped, will result in a substantial degree of stressing of springs 27. As each piston reaches the end of its upward stroke, it effects the release of that one of two latches 34, which has theretofore been restraining a valve operating lever 35 from movement under the force of the drive spring 29. When this lever is released, and if the valve lever is otherwise 85 free to move, the springs 27 previously stressed as described, suddenly relieve their stress and impart a quick, sharp, downwardly-directed impulse to one of the pistons to start it on its downward and discharge stroke. 90

When an elastic connection is interposed in the connections between the pistons, for either of the two purposes described, it is essential, in order to guard against improper 100 operation of the apparatus, to prevent operation of the valves until both pistons have completed their strokes. Operation of the valves cannot occur until the rising piston is arrested by abutment 32 which occurs simultaneously with the release of valve lever 35 by latch 34. Normally the descending piston would have been arrested by abutment with base 25 before this time, but if the pumping is extremely rapid and/or the discharge is sluggish because of a crooked or trapped hose or for other reasons, the resistance to movement of the descending piston may be such as to cause springs 27 to yield before the appointed time. While this is 110 not the normal condition, it is one that can occur and one that needs to be guarded against. 115

As a safe-guard against such trouble, the valve operating mechanism is provided with a supplementary locking device 120 36 (Fig. 10), engageable in either of two notches 37 in a disc 38, secured to the same shaft 39, which carries the valve operating lever 35. This locking device 36 is arranged to be withdrawn from holding engagement 125 with disc 38 by either piston but only at the end of the discharge or descending movement thereof. Thus, the valves cannot operate until the rising piston completes its upward stroke and releases latch 34 and until 130

the descending piston completes its downward stroke and releases the locking device 36. In this way, the apparatus cannot be made to work in any way other than that planned notwithstanding that an elastic, and therefore yieldable, element is interposed in the connection between the two pistons.

Referring to the details of the valve mechanism, each valve 28 consists of a ported circular disc (Fig. 12) which is set into a recess 40 (Fig. 15) in the base 25 of its cylinder with its upper face (Fig. 14) flush with the upper face of such base. Each valve 28 has two diametrically opposed ports 41 (Figs. 12 and 14) extending vertically therethrough. In the base of each recess 40 are two diametrically opposed discharge ports 42 (Figs. 14 and 15) and all four of these ports communicate with an underlying discharge passage 43 (Fig. 14) which is formed in base 25, and best shown in Fig. 13. Also formed in the bottom wall of each recess 40 is an inlet port 44 and these two ports communicate with an underlying inlet passage 45 (Fig. 13). Each valve is fixed to the upper end of a stem 46 which extends downwardly through and below casting 25, carrying on its lower end an arm 47 (Fig. 14).

These two arms 47 are interconnected by a link 48, which has a central recess 49 of inverted U-shape to receive a roll 50 (Fig. 10) carried on the upper end of an arm 51. The latter at its other end, is fixed to the valve operating shaft 39 (Fig. 11) and, in cooperation with a collar 52 on such shaft, holds the shaft against undue endwise movement in its support 53. The latter is a hollow casting, suitably secured as indicated to the lower face of base casting 25 and depending centrally therefrom. It will be clear that when the valve operating lever is actuated to turn shaft 39, both valves 28 will be simultaneously turned. The limit of this turning movement is ninety degrees and each valve 28 can turn from a position, wherein both ports 41 register with both discharge ports 42, to a position wherein one of the ports 41 registers with the port 44. In this way, the valve connects its measuring cylinder to the supply or discharge passages 45 or 43, respectively. From Fig. 12, it will be clear that when one valve 28 connects its cylinder 20 to the supply passage, the other valve is positioned so as to connect its cylinder 20 to the discharge passage. Thus, one measuring cylinder fills while the other discharges.

Means are provided for holding each valve against lifting from its seat in recess 40 under the pressure of the liquid pumped into passage 45 and such means is preferably adjustable to compensate for wear. As herein shown, this means includes a nut 54 threaded onto the lower end of the valve stem 46 and

held in adjusted position by a check nut 55. Nut 54 acts to draw down the valve stem by pressing against the valve arm 47, which is slidably connected by a key 56 to stem 46. The upper part of arm 47 preferably bears against a ball bearing 57, which in turn bears against the lower end of a sleeve 58. The upper end of sleeve 58 bears against the under face of casting 25. Within sleeve 58 is a spring 59, which acts between the ball bearing 57 and a gland 60 to compress the packing 61 in the stuffing box formed in casting 25, and thereby prevent leakage around valve stem 46. Leakage around the piston rods 24 is prevented by similar stuffing boxes shown in Fig. 14. The glands 62 of these boxes are pressed upwardly by a pair of springs 63 (Fig. 10) acting against the heads of a pair of studs 64 secured to casting 25.

The casting 53 is hollow (Fig. 7) affording a passage 65 which communicates as indicated in Figs. 11 and 13 with supply passage 45. To the lower end of casting 53 is bolted a vertically depending cast-pipe section 66, to the lower end of which is connected the supply pipe 67 for liquid under pressure. Near the lower end of the pipe section 66 are a pair of diametrically-opposed, radially-extending arms 68 in each of which is fixed a depending tube 69. The tubes 69 slidably receive and guide the piston rods 24. The arms 68 also serve to support the lower ends of a pair of fixed guide rods 70, disposed one directly behind each piston rod 24 (Fig. 10),—the upper ends of these rods being received in suitable sockets in the base casting 25.

Referring next to Fig. 9 and the connections between the two piston rods, each rod 24 has fixed thereto an arm 71 and in each of these arms a rod 72 is mounted to slide in a direction parallel to the axis of the piston rod. The springs 27, above described, are applied one to each of these rods. Each spring acts between the upper face of arm 71 and an adjustable abutment 73 on its rod, tending to lift the latter until a head 74 on the lower end of the rod abuts the lower face of arm 71. The chain 26, above referred to, is connected at its ends, one to each of the heads 74. This chain is suitably guided intermediate its ends, as by a pair of grooved rolls 75 mounted one on each of the arms 68, so that the two vertical stretches of the chain are substantially parallel and in alignment with the axes of the rods 72, to which they are connected. It will be clear that when one piston 21 is arrested in its downward stroke, as by abutment with base 25, the other can continue to rise because the springs 27 will yield by compressing to permit such action.

It has been stated that the valve operating lever is held by either of a pair of latches

34 and that this lever is released, when the rising piston reaches the upper end of its stroke. These latches (Fig. 9) are pivoted on studs 76 secured to casting 25. The free end of each latch rests on top of a head 77, formed on the upper end of a rod 78, which is mounted for vertical sliding movement in a bearing 79. These bearings are formed, one on each outer end of a bar 80, secured by bolts 81 to casting 53. A spring 82 connects each latch 34 to the adjacent bearing 79 and tends to hold its latch and rod 78 in the illustrated position, in which head 77 abuts the upper end of bearing 79. Adjustably mounted on the lower end of each rod 78 is an abutment 83. These abutments 83 are located, one in the path of each of a pair of arms 84, secured one to each piston rod 24 and preferably formed as a part of the described arm 71. When the left hand piston is rising, the valve lever 35 is restrained by the left hand latch 34 and this latch will be released after arm 84 has engaged abutment 83 and lifted it far enough for the purpose. The actual release occurs simultaneously with the engagement of the abutment 82 on the rising piston with the overlying and fixed abutment 83. When the right hand piston is rising, lever 35 is restrained by the right hand latch 34 and this latch will be released in a similar way and at a similar time by movement of the right hand arm 84.

The locking device 36, which also controls the time of movement of shaft 39 and thus the time of operation of valves 28, will be described with particular reference to Figs. 10 and 11. This device consists of a piece of square cross section formed on the upper end of a rod 85, which slides vertically in a lug 86, formed on and projecting rearwardly from casting 53 near the lower end thereof. The rod 85 has a keyway 87 in which is engaged a pin 88 fixed in lug 86, whereby to hold lock 36 from turning during its sliding movement and in proper position for entry into the notches 37 of the locking disc 38. Rod 85, at its lower end, is threaded into a sleeve 89 fixed to the upper end of a rod 90. Rod 85 can therefore be raised or lowered with respect to rod 90 for purposes of adjustment, although in all other respects it is virtually a part thereof. Rod 90 is vertically slidable in upper and lower guides 91 formed on the back side of pipe 66. Fixed at a point intermediate its ends to rod 90 and located also between the upper and lower guide 91 is a cross bar 92. A spring 93, acting between the top of the upper guide 91 and a collar 94 fixed on rod 90, tends to lift the latter and hold lock 36 engaged in one of the recesses 37. The rising movement of the rod is limited by the abutment of cross bar 92 with the bottom of the upper guide 91. The outer ends of cross bar 92 are slidably engaged one with each guide rod 70. An arm 95 is

fixed to and projects rearwardly from each piston rod 24 with its rearward end slidably engaged with rod 70 and overlying the adjacent end of cross bar 92. These arms 95 are so located on their respective piston rods as to engage and move cross bar 92, and thus lock 36, near the lower end of the stroke of their pistons. The arrangement is such that the moment that lock 36 is completely withdrawn from a recess 37 coincides with the moment that a piston 21 abuts its base 25. Each piston operates to release the one lock 36 in the manner and at the time described.

The valve lever 35, which as above described is positively held against movement until one piston reaches the upper end of its stroke and the other reaches the lower end of its stroke, is moved extremely rapidly when released by the drive spring 29. The latter is coiled around a rod 96 (Figs. 9 and 11) and acts between a forked head 97 on one end of that rod and a collar 98, which is swivelled in and projects forwardly from the valve lever 35. Rod 96 is free to slide in piece 98. Fork 97 is pivoted to the upper end of a lever 99 and the latter is pivoted intermediate its ends on a stud 100, fixed to a bracket 101, bolted to the front face of casting 53. During the driving of lever 35 by spring 29, lever 99 is stationary, being held so, as will later appear, either in the illustrated position or in a corresponding angular position on the opposite side of a vertical line extending through the center of the pivot 100. The spring 29, as shown, is fully stressed. Consequently, when lever 35 is released, spring 29 will expand and move lever 35 to the right. This movement of lever 35 is limited by its engagement with a fixed abutment 102 on cross bar 80. A similar abutment is provided on bar 80 to define the extreme left hand or illustrated position of lever 35.

Assuming that lever 35 has moved to the right and engaged the right hand abutment 102, the valves 28 will have been reversed from the illustrated positions and the right hand piston will start upwardly and the left hand one downwardly. As the right hand piston rod 24 moves upwardly, a spring 103, coiled therearound and resting on arm 71, engages and lifts a member 104, through which the piston rod 24 slides. This member is connected by a link 105 to one end of a lever 106, which is fixed at a point intermediate its ends to the rear end of a shaft 107. The latter is mounted in a bearing 108 formed on a frame 109, which is an integral part of the cast pipe section 66. Fixed at a point intermediate its ends to the front end of shaft 107 is a lever 110, the upper end of which carries a roll 111 to ride in a recess 112 in the lower end of the above described lever 99. Thus, as rod 24 rises, levers 106 and 110 will be rocked in a counterclockwise direction, forcing lever 99 to swing clockwise.

Such movement will force head 97 against spring 29 and compress it against the swivelled collar 98. The force, then applied to stress the drive spring 29, is so directed as to hold lever 35 against abutment 102. However, near the end of this spring-stressing movement of lever 99, its point of pivotal connection with rod 96 will cross to the right of a line connecting the center of shaft 39 and the center of oscillation of collar 98. The result is that the force of the spring on lever 35 will then be so directed as to tend to move the lever to the left, just as such force with the parts positioned as illustrated in Fig. 9, is so directed as to tend to move lever 35 to the right. This lever 99 therefore has two functions,—to stress the drive spring and to position it properly so that it can move lever 35 in the proper direction at the proper time. In order to hold lever 99 stationary during the driving of lever 35 by spring 29, the lower end of lever 110 is bifurcated, presenting two angularly spaced surfaces 113 and one or the other of such surfaces abut a fixed stop 114 on frame 109 at such times.

It will be noted that lever 106 is connected by a similar link 105 to a sliding member 104 on the left hand piston rod 24 and that such rod carries a spring 103, whereby when the left hand piston 21 is ascending, lever 106 can be rocked clockwise to cause a counter-clockwise movement of lever 99 into the illustrated position. The parts 104 are moved from the piston rods 24 through springs 103 so that, after such parts have been moved as far as possible (until one or the other of the surfaces 113 has engaged stop 114), the springs can yield and permit continued upward travel of the piston rods to an extent sufficient to enable arms 84 to effect the release of the latches 34.

From the preceding description, it will be clear that the measuring cylinders, and all of the mechanism associated therewith for operating and controlling the operation of the valves thereof, are carried by the base casting 25. This member may be supported in any suitable way. As an illustrative example of one such way, the following supporting frame and enclosing housing for said mechanism may be used. Four pipe columns 115 connect base casting 25 to an intermediate member 116, which in turn is supported by three pipe columns 117, from a base 118, adapted to be bolted to a suitable foundation. A two part shell 119, of circular cross section, encloses the space between members 116 and 118 while a two part shell 120 of square cross section, encloses the space between base casting 25 and member 116. These shells 119 and 120 are secured to the members, against which they abut, in the usual or any suitable manner. The lower shell 119 is usually provided with hinged doors, such as 121 and 122 which, when

opened, uncover the openings 123 and 124, respectively, shown in Fig. 8. Access to the space within housing 120 is not ordinarily required and, in order to prevent convenient access thereto by way of opening 123, closure plates 125 and 125' are secured to the member 68 and housing 119, respectively, as shown in Fig. 8. The tubes 69, above described, are preferably closed at their lower ends to prevent manipulation of the piston rods 24, which at times extend below plate 125 and would otherwise be accessible through opening 123.

The measuring cylinders 20 may be mounted in any suitable manner. As shown in Fig. 7, each is surmounted by an annular ring 126 and as shown in Fig. 6, a cross bar 127 extends diametrically across this ring with its ends resting thereon. A pair of tie rods 128, threaded at their lower ends into base casting 125, pass through ring 126 at opposite points thereon and through the overlying ends of cross bar 127. Long hexagonal nuts 129 are threaded on the upper ends of tie rods 128 and serve to clamp the cross bar to ring 126, the latter to the top of cylinder 20 and the cylinder to base 25. The rods 130 are dummy rods. The cross bar 127 serves to support the described abutment 33, which is threaded into and therefore vertically adjustable with respect to the cross bar. Each measuring cylinder is preferably closed, as by a disc 131, secured as indicated in Fig. 7, to ring 126. The upper ends of the two cylinders are interconnected by piping 132 which has an opening at 133 to the atmosphere. Usually a hood 134 surmounts the cylinders 20 and this may be supported as shown in Fig. 6 from the nuts 129 and secured thereto as indicated. Hood 134 usually carries an illuminated globe, such as that shown in Figs. 1 and 2 at 135.

The preferred construction of the pistons 21 and the float controlled air valves therein is shown in Figs. 3 and 4. The cupped piston leather 136 is clamped between upper and lower members 137 and 138, respectively, and these members are secured together by cap screws 139. The member 137 is an annular ring and member 138 has a central upstanding cylindrical part extending into this ring to center it. The piston leather 136 is pressed against the wall of its cylinder 20 by a coil spring 140, mounted in a circumferential groove in member 128 and preferably stuffed with packing 141. The piston rod 24 passes through member 138 and through an overlying baffle plate 142 and is secured thereto by a nut which constitutes the described abutment 32. Member 138 has a central recess 143 of such size as to closely fit the described float 23, leaving freedom for just sufficient vertical movement of the float to enable it to open vents 22 without passing out of the recess 130.

to any extent. The vents 22, of which there are three, extend through the upper wall of recess 143. The float slides freely on the piston rod 24 and may rest at times on base 25. When such is the case, as liquid enters the base of a measuring cylinder, it carries the float upwardly as indicated in Fig. 5, and eventually into recess 143 into the position shown in Fig. 3, wherein all three vents are 10 closed directly by the upper face of the float. To facilitate the outflow of air by way of recess 143 and vents 22, the lower face of member 138 is slotted, as shown at 144. The arrangement is such that the volume of liquid 15 which can enter into member 138 by way of grooves 144, recess 143, or around the spring 140, is exceedingly small with reference to the volume displaced from a measuring cylinder by a full stroke of the piston and well 20 within the tolerances of measurement usually permitted.

Liquid may be forced into the supply pipe 67 by any suitable means. As an example 25 of one of many such means, I show a hand operated pump 145 (Figs. 7 and 8), having an oscillatable operating shaft 146, to the outer end of which is fixed a member 147. An operating handle 148 is pivoted at 149 to member 147 so that it may be swung from 30 the position shown by dotted lines in Fig. 8, wherein it is entirely enclosed in housing 119, to the position shown by full lines, wherein the handle lies sufficiently outside the housing to enable it to be rocked back 35 and forth, in a plane at right angles to that in which it swings on pivot 149, to operate the pump. The pump 145 is supported, preferably in a manner such as to permit convenient removal, from a frame 150, secured 40 as indicated to pipe column 117. As shown, the pump has a depending part 151 which is clamped between pairs of screws 152, mounted in a pair of upstanding lugs 153 on frame 150. The suction pipe of the pump 45 is shown at 154 and is adapted for connection to an underground supply tank. Interposed in pipe 154 is a suitable filter 155, accessible through door opening 124. The discharge pipe of the pump is shown at 156, and 157 is 50 a by-pass from the discharge to the suction pipes around the pump. This by-pass is normally closed by a valve 158 which opens automatically, whenever the pressure of the pumped liquid in discharge pipe 156 exceeds 55 a predetermined degree, and permits such liquid, or a part thereof, to return to the suction pipe 154.

While the discharge pipe 156 might be directly connected to the above described pipe 60 67, I prefer to interpose between these pipes an air separator. The separator shown is of a known type and includes a tank 159 connected at its lower end to pipe 156 and at its upper end to pipe 67 and otherwise closed except for the outlet 160 in the top wall thereof.

Pipe 156 communicates at all times with a central upstanding pipe 161 in the tank and this pipe terminates near the top of the tank with an open upper end. Pipe 67 communicates at all times with a pipe 162 which extends downwardly in the tank, terminating near the bottom thereof with an open lower end. Outlet 160 is connected by a pipe 163 to a pipe 164, which extends downwardly in housing 119 and is adapted for connection to the top of the underground supply tank. Slidably encompassing pipe 161 is an annular float 165 carrying a valve 166, adapted when the liquid level in tank 159 rises sufficiently, to close outlet 160. At all other times, the outlet is open to permit the escape of air. Since this air is saturated with gasoline vapor and since some gasoline may at times escape through outlet 160, the latter is connected to the gasoline tank as described. Float 165 carries a cross bar 167 which limits the downward movement thereof by engagement with the top of pipe 161. This cross bar passes diametrically across, without closing off the upper end of pipe 161.

Preferably, means are provided for insuring that the measuring cylinders 20 are drained when pumping ceases. Of course, that cylinder 20, which happens to be connected to the discharge passage, will empty itself into such passage because float 23 will open vents 22 and enable the draining. The other cylinder, which is then connected to the inlet passage, might have been partially full when pumping ceased and, in order to drain that cylinder, I connect to the inlet pipe 66, at some convenient point, a pipe 168 (Fig. 11) which extends upwardly inside housing 120 to about the level of the base of casing 25 and is there connected to the above described return pipe 164. An air admission valve, or "siphon breaker" 169 is connected to the upper end of pipe 168. When pumping ceases, that cylinder 20 which is in communication with pipe 66 through the passages 45 and 65, will drain through pipes 168 and 164 and will be completely emptied. Liquid will also drain out of the inlet passage 45 and down to the level of the siphon breaker 169.

For the purpose of indicating the number of unit measured quantities delivered from the apparatus, I provide a suitable register 170 and mechanism for operating it in such a way that the register counts the number of operations of the valve lever 35. The register is supported from the frame 109 by three studs 171 which are shown in section in Fig. 9. In Fig. 11, one of these studs has been broken away but it will be clear that they project forwardly through a circular opening 172 in shell 120 and that the back plate 173 of the register abuts the ends of these studs, being secured thereto by cap screws 174. The opening 172 is large enough to permit the shell 120 to be removed without disturb-

ing the register and the shell has fixed there-
to a ring 175, which encompasses the plate
173 and conceals the opening. Fixed to the
inner face of plate 173 is a frame 176 in which
the register operating shaft 177 is mounted.
This shaft has fixed to its inner end a ratchet
178. In back of the ratchet and arranged to
swing freely in the space between the front
end of shaft 107 and the rear end of shaft
177 is a lever 179, which as shown in Fig. 9
is approximately Y-shaped and pivoted on
a stud 180 secured to hub 114. One of the
two upwardly diverging arms of this Y-
shaped lever carries a pawl 181 for actuati-
ing the ratchet 178. A holding pawl 182 is
pivotally mounted on stud 180 and these
pawls are interconnected by a coil spring 183,
which lies in front of the ratchet (Fig. 11)
and tends to hold both pawls in engagement
therewith. The other of the aforesaid arms
has a rearwardly projecting hub 184 which is
connected by a link 185 to a fork 186. The
latter is adjustably secured to a rod 187 which
is mounted for vertical sliding movement in
the hub of the bracket 101, above described.
The upper end of rod 187 underlies one or
the other of a pair of cams 188, formed on
the lower end of valve lever 35, and is held
in engagement therewith by a spring 189
which connects a pin on said hub to link 185.
The connection between rod 187 and fork 186
is such as to permit the effective length of
these combined pieces to be increased or de-
creased. As the valve lever 35 swings from
one to the other of its two extreme positions,
one or the other of the cam faces 188, will
depress rod 187 and thereby rock lever 179 in
a counterclockwise direction. Such move-
ment of this lever will cause pawl 181 to ad-
vance ratchet 178 by one step and turn shaft
177. The latter has a crank 190 (Fig. 11) on
its outer end, the crank pin 191 of which en-
gages the usual operating crank 192 of the
register and crank 192 will, by the usual
mechanism (not shown) of the register 170,
cause an appropriate movement of the regis-
ter hand 193 (shown in Fig. 1). The ratchet
is moved only during the first half of each
movement of the lever 35 and, on the other
half of such movement, rod 187 is permitted
to rise under the influence of spring 189,
which causes pawl 181 to move back into its
original position,—the ratchet 178 being held
against movement by pawl 182.

In operation, pump 145 is operated by os-
cillating handle 148 and liquid is forced up-
wardly through pipe 156, through the air
separator 159, and thence through pipes 67
and 66 into passage 65 and finally into inlet
passage 45. From this passage it will flow
out through one of the inlet ports 44 (that
which is then uncovered by the overlying
valve 28), into one of the measuring cylin-
ders 20. The liquid, entering such cylinder
at a point beneath its piston, raises such pis-
ton, first driving out through the vents 22,
if necessary, any air which may be in the cyl-
inder. When such air has been substantially
all driven out through vents 22, the latter are
closed by float 23 and the piston rises. As
one piston rises, the other is forced to descend
due to the interconnection of the two piston
rods by the chain 26 and springs 27. The
descending piston normally reaches the lower
limit of its stroke, and is arrested by abut-
ment with base 25 before the rising piston
reaches the upper limit of its stroke, with the
result that continued upward movement of
the rising piston causes springs 27 to be
placed under stress. As soon as either piston
reaches the lower limit of its stroke, the lock
36 is withdrawn from holding engagement
with disc 38, thus releasing the valve mecha-
nism at this point. The latter, however, is
not free to operate until the rising piston has
completed its upward stroke, when that latch
34 which has been restraining lever 35 from
movement, is released. When both this latch
and lock 36 are released, the drive spring 29
expands and drives lever 35 over and against
the right hand abutment 102. This causes
the valves 28 to be simultaneously moved and
into such position as to connect the right hand
cylinder 20 to inlet passage 45 and the left
hand cylinder to discharge passage 43. The
right hand piston then descends and pulls the
left hand piston down to express from the left
hand cylinder the liquid previously pumped
therein. The discharge stroke of the left
hand piston, however, is initiated much more
suddenly because, just as soon as the valves
28 operate, the previously stressed spring 27
impart a spring impulse to such piston to
start it on its downward stroke. Before the
right hand piston has reached the upper end
of its stroke, the left hand piston, under nor-
mal conditions, will have completed its dis-
charge stroke and released lock 36. Filling
of the right hand cylinder continues until the
piston therein is arrested by abutment 33, at
which time the proper latch 34 is withdrawn
from holding engagement with lever 35 and
the latter is again moved by spring 29 into
its left hand and illustrated position.
Valves 28 are again operated to reverse the
connections to the measuring cylinders 20 and
the left hand cylinder begins to fill while the
right hand cylinder discharges,—the dis-
charge being initiated as before by a spring
impulse. The described action continues as
long as pumping continues. On cessation of
pumping, that cylinder which is then in the
process of being filled will drain through
pipes 164 and 168 and no liquid will ordi-
narily remain in either cylinder. This fol-
lows because it is usual to stop pumping after
one piston has completed its discharge stroke
and before the other has completed its filling
stroke. In other words, one piston will be

in abutment with base 25 and all liquid therein will have been forcibly discharged.

It will be clear that if there is unusual resistance to the descent of the discharging piston, the rising piston may cause the springs 27 to yield and not draw the discharging piston down as rapidly as the other rises. Extremely rapid pumping will cause the same result. In either case, or in any other case 10 where yielding of the springs occurs before the normal time, one piston may reach the upper limit of its stroke and cause the release of lever 35 from latch 34. The lever 35, however, cannot then be moved by drive spring 29 because the shaft 39, to which it is fixed, will be held by lock 36 until the discharging piston completes its down stroke and abuts base 25 at which time the lock is released.

This double lock for the valve mechanism 20 is of particular importance in an apparatus of this special kind, where a spring impulse drive of the pistons is desired. Such drive necessitates the use of springs and these necessarily can, under some conditions, yield 25 at other than the desired times. The double-lock feature enables the desirable spring impulse to be used to initiate the discharge stroke of the pistons without permitting the pistons to get out of the desired timed relation. An apparatus of this special type is thereby rendered substantially fool-proof by the double-lock feature.

Aside from this feature, the valve arrangement is thought important particularly with 35 respect to the mounting of the valves one in the base of each cylinder. In this way, the piston abuts the upper face of the underlying valve at the same time it abuts the base 25 and all liquid, except the small quantities in 40 the piston recesses and grooves, is forcibly expelled, passing into the discharge passage 43, from which all liquid can drain, when necessary, as on cessation of pumping.

The invention has been disclosed herein, in 45 an embodiment at present preferred, for illustrative purposes but the scope of the invention is defined by the appended claims rather than by the foregoing description.

What I claim is:

1. Liquid dispensing apparatus, comprising, a pair of measuring cylinders, a piston in each of said cylinders, liquid forcing means, valve mechanism for alternately connecting said cylinders to said means and for enabling liquid to discharge from either cylinder while the other is being filled, connections between said pistons by which each piston when moved on its filling stroke by liquid entering one cylinder will move the other piston to discharge liquid from the other cylinder, said connections including elastic means stressed by each piston during the latter part of its filling stroke and initiating with a spring impulse the subsequent discharge stroke of such piston, and means for

locking said valve mechanism against operation until one piston has completed its filling stroke and the other its discharge stroke.

2. Liquid dispensing apparatus, comprising, a pair of measuring cylinders, a piston in each of said cylinders, liquid forcing means, valve mechanism for alternately connecting said cylinders to said means and for enabling liquid to discharge from either cylinder while the other is being filled, connections between said pistons by which each piston when moved on its filling stroke by liquid entering one cylinder will move the other piston to discharge liquid from the other cylinder, said connections including elastic means stressed by each piston during the latter part of its filling stroke and initiating with a spring impulse the subsequent discharge stroke of such piston, and locking means for said valve mechanism releasable in part by one piston when it reaches the end of its filling stroke and in part by the other piston when it reaches the end of its discharge stroke.

3. Liquid dispensing apparatus, comprising, a pair of measuring cylinders, a piston in each of said cylinders movable between fixed limits, liquid forcing means, valve mechanism for alternately connecting said cylinders to said forcing means and for enabling either cylinder to discharge while the other is being filled, means interconnecting the pistons whereby either when moved during the filling of its cylinder will move the other to discharge the liquid from its cylinder, said connections normally causing each piston to reach the fixed limit of its discharge stroke before the other piston reaches the fixed limit of its filling stroke, elastic means included in said connections permitting continued travel of either piston after the other has reached the limit of its discharge stroke, means for moving said valve mechanism, and means restraining the last named means from moving the valve mechanism until one piston has reached the limit of its filling stroke and the other piston the limit of its discharge stroke.

4. In a liquid dispensing apparatus, a pair of cylinders, a piston in each cylinder movable between fixed limits, connections between said pistons forcing them to move in opposite directions and arranged so that each piston normally reaches one of its limits before the other piston reaches the opposite limit, said connections including elastic means which permit the travel of either piston after the other has reached one of its limits and which are stressed by such travel, valve means for alternately admitting liquid under pressure to said cylinders and for enabling one cylinder to discharge while the other is filling, said elastic means being stressed during the filling of each cylinder and relieving its stress at the start of the discharge of that cylinder, and means controlling the time of operation

of said valve means and necessitating as a condition precedent to such operation that the discharge stroke of one and the filling stroke of the other be completed.

5. In a liquid dispensing apparatus, a pair of measuring cylinders, a piston in each cylinder, a flexible member serving to interconnect the pistons, guiding means to so direct said member that the pistons are forced to move in opposite directions, elastic means interposed in said flexible connection between the pistons, valve means for admitting liquid alternately to one end of each cylinder and for discharging liquid from such end of one cylinder while the other is being filled, whereby one piston is moved by the liquid supplied to its cylinder under pressure and moves the other piston to force the liquid out of the other cylinder, means for arresting each piston at the end of its discharge stroke normally effective before the other piston has reached the end of its filling stroke, whereby said elastic means is normally stressed near the end of the filling stroke of each piston and imparts a spring impulse to such piston to initiate its discharge stroke, and means controlling the time of operation of said valve means and necessitating as a condition precedent to such operation that the discharge stroke of one and the filling stroke of the other be completed.
6. In a liquid dispensing apparatus, a pair of upstanding cylinders disposed side by side, a piston in each cylinder having a piston rod depending through one end thereof, a flexible member, elastic means through the intermediary of which the ends of said member are connected one to each piston rod, guiding means directing said member to travel in a path in part parallel and adjacent to one piston rod, across towards the other piston rod and then parallel and adjacent to the last named rod, valve means for alternately admitting liquid under pressure to the lower ends of said cylinders and for enabling one cylinder to discharge while the other is filling, whereby the liquid supplied to one cylinder raises the piston therein and through said flexible member lowers the other piston to forcibly expel the contents of the other cylinder, means for arresting each piston at the end of its discharge stroke and normally effective before the other piston has completed its filling stroke, whereby said elastic means will be stressed and impart an impulse to start each piston on its discharge stroke, and two means for locking said valve mechanism one of which is releasable by either piston rod at the end of the upstroke thereof and the other of which is releasable by either piston rod at the end of the downstroke thereof.
7. Liquid dispensing apparatus, comprising, a pair of upstanding measuring cylinders mounted side by side, a piston in each cylinder having a piston rod extending through the bottom wall of its cylinder, oscillatory valves mounted one in the base of each cylinder for alternately admitting and discharging liquid therefrom, valve stems extending one from each valve through the base of its cylinder, means interconnecting said valve stems so that when one valve is in position to admit liquid to its cylinder the other valve is in position to discharge liquid therefrom, a spring impulse mechanism for operating said interconnecting means first in one and then in an opposite direction, means operable by movement of said pistons for stressing said impulse mechanism, and means for restraining said mechanism from moving said valves until one piston reaches the end of its filling stroke and the other the end of its discharge stroke.
8. Liquid dispensing apparatus, comprising, a pair of upstanding measuring cylinders mounted side by side on a common base member, a piston in each cylinder having a piston rod passing downwardly through said member, connections between said rods forcing them to move in opposite directions, oscillatory valves mounted in said member and located one in each cylinder with their stems extending through and below said member, an oscillatory drive shaft and connections between it and said stems, spring impulse mechanism located below said member and between said rods for rocking said shaft first in one and then in the other direction, two independently operable means for locking said shaft against movement, means carried by each piston rod effective at the end of its upward stroke to release said shaft from one of said locking means, means carried by each piston rod effective at the end of its downward stroke to release the other of said means, and means operable by the piston rods intermediate the ends of their strokes to stress said impulse mechanism and render it effective when released to actuate said shaft.
9. In a liquid dispensing apparatus, a measuring cylinder having a head provided with a valve recess and intake and discharge ports in the bottom wall of such recess, an oscillatory disc valve mounted in said recess and seated on said wall with its upper face flush with the upper face of said head, said valve being movable to cover and uncover said ports in alternation, means for holding said valve to its seat against axial movement, and a piston in said cylinder having a flat lower face to abut said head and valve.
10. In a liquid dispensing apparatus, a measuring cylinder having a head at one end thereof provided in its inner face with a valve recess and with intake and discharge ports leading into said recess, a valve in said recess mounted to turn but held against axial movement in said head and movable to cover and

uncover said ports in alternation, and a piston in said cylinder arranged to abut said face of said head, the abutting surfaces of said piston and head being complementarily formed to enable substantially all liquid between them to be expelled from the cylinder through the adjacent discharge port.

11. In a liquid dispensing apparatus, a measuring container having in one end thereof a valve seat with intake and discharge ports therein, a disc valve overlying said seat and movable to cover and uncover said ports in alternation, means for supplying liquid under pressure to the intake port at all times while the apparatus is in operation including such times as the intake port is covered by said valve, the liquid pressure through the intake port tending to move said valve away from its seat, and means for holding said valve to its seat against said liquid pressure.

12. In a liquid dispensing apparatus, a measuring container having in one wall thereof a valve seat and intake and discharge ports therein, a disc valve engaging said seat and movable to cover and uncover said ports in alternation, a stem for said valve turnably and slidably mounted in said wall and projecting therebeyond, resilient means for drawing said stem axially outward to hold said valve tightly against its seat, said means including an interposed anti-friction bearing associated with the stem to enable the latter to turn freely although under the axially directed pressure of said resilient means, and means for turning said stem.

13. In a liquid dispensing apparatus, a measuring container having in one wall thereof a valve seat and intake and discharge ports therein, a disc valve engaging said seat and movable to cover and uncover said ports in alternation, a stem for said valve turnably and slidably mounted in said wall and projecting therebeyond, resilient means for drawing said stem axially outward to hold said valve tightly against its seat, and means for turning said stem including a member slidably but non-rotatably engaged with said stem, whereby the stem may move axially under the influence of said resilient means without interference with the means for turning the stem.

In testimony whereof I have affixed my signature.

55 ALFRED L. GRISÉ.
